UNITED STATES PATENT OFFICE.

WASHINGTON R. PITTS AND GEORGE K. GLUYAS, OF SAN FRANCISCO,
CALIFORNIA.

IMPROVEMENT IN STEAM-CONDENSERS.

Specification forming part of Letters Patent No. 131,779, dated October 1, 1872.

To all whom it may concern:

Be it known that we, WASHINGTON R. PITTS and GEORGE K. GLUYAS, of the city of San Francisco, in the county of San Francisco and the State of California, have invented a new and Improved High-Pressure Condenser, to be used more especially upon side-wheel high-pressure steamboats to condense the steam that escapes from the cylinder or cylinders and return the condense-water back to the force-pumps to be used in the boilers, *ad infinitum*; and we do hereby declare that the following is a full, clear, and exact description of the construction and operation of the same, reference being had to the annexed drawings making a part of this specification.

Similar letters of reference indicate corresponding parts.

To illustrate more clearly the application of our invention, we give three views of the condenser and eight sectional views of portions of the same.

Figure 1 is a plan of the condenser, the chambers A showing the direction in which the steam travels through it by the dotted arrows, from its entrance at the pipe a, (which pipe may be placed on the cover as drawn, or on the top of chamber A, as may be most convenient,) to its escape through pipe b, (provided any portion of the steam is not condensed,) which has a rubber valve set on a grating, that may be used or not, at the option of the engineer. c, in dotted lines, is a pipe with branches to convey the condense-water out through c c to the hot well or reservoir to supply the boiler feed-pumps. d, in dotted lines, marks the partitions in the chambers A at either end. l represents the heads to close up chambers A, (and can be made in one or more pieces;) g, tubes; h, cover over opening to pipe c, to prevent the steam from backing up the condense-water; n, a graduated vacuum-valve.

Fig. 2 is an end elevation of the condenser, showing the cover l partly off, the tubes g, the partitions d, exhaust-steam entrance a, man-holes m, condense-water pipe c opening into c c, cover h, valve-seat b, rubber valve k, and section of escape-pipe i.

Fig. 3 is a side elevation of the condenser with chambers A, tubes g, showing the direction of

the steam by the dotted arrows, as in Fig. 1, entrance at a, escape at b, through pipe i and rubber valve k, (the pipe i can be made of any desired form with outlet in wheel-house or through the upper deck of boat,) condense-water pipe c leading to outlet c c; h, cover over outlet c.

Fig. 4 is an enlarged view of rubber valve k as prepared for use; Figs. 5 and 6, enlarged plan and end views of valve-seat and grating b for rubber valve; Figs. 7 and 8, enlarged side and end view of covers h; Figs. 9 and 10 enlarged plan and edge views of a round valve-seat and grating b for rubber valve; Fig. 11, enlarged view of round rubber valve k as prepared for use.

To enable others skilled in the art to make and use our invention, we will proceed to describe its construction and operation, with the advantages to be derived by its use.

As regards its construction, the drawings are marked and lettered, so that any mechanic can construct the various parts of the "condenser" by reference to the same. The chambers, covers, and partitions are made of boiler-iron, (cast-iron can be used,) with ordinary boiler-tubes, and for its operation and advantages we would say that this "condenser" is more particularly applicable to side-wheel "high-pressure steamboats," and may be used on other high-pressure steamboats, and on land where a sufficient volume of water can be obtained to flow over the condenser chambers and tubes. The general form of its various parts may be modified to suit space and distances, and can be made either square, round, or parallelogram, and for side-wheel high-pressure steamboats is placed on the after-side of the wheel in the wheel-house, resting on a suitable framing, and to be protected from the drift-wood and ice by having either wood or iron braces over the chambers and tubes, the condenser to be raised to a sufficient height to allow the condense-water to flow back to the hot well or reservoir; and its mode of operation is as follows: The steam, on leaving the cylinder, passes into the "heater," (of whatever form it may be,) imparting a portion of its heat to the water therein, and the uncondensed portion of the steam then passes into the "condenser" in the wheel-house, where it is con-

densed by the water and spray from the paddle-wheel, and the condense-water then flows back to the hot well or reservoir at a temperature of from 130° to 160° ; the water then supplies the "doctor" or engine-pumps, and thence is pumped into the heater, where the water is further heated to from 190° to 208° of heat, and thence passes into the feed-drums for supply of boilers.

We would advise on new steamboats the use of "tubular heaters," feeding through the tubes; exhaust around them the proportion one cubic foot of cylinder to twenty-two square feet of tube-surface, and the proportion of the condenser one cubic foot of cylinder to nineteen square feet of tube-surface. Tubes of one-inch inside diameter are the best to use—two-inch diameter will answer—the area of the tubes in first compartment of the condenser to be as large as the exhaust-steam pipe, and diminishing gradually in each compartment, as shown in the drawings annexed.

The covers *h* are placed over the outlet *c*

for the purpose of protecting the outlet-pipe *c c* from too great a pressure of water in the chambers *A A*, and to cause the water to spread in passing under the covers, thus preventing eddies from drawing exhaust steam and air into the outlet.

We do not claim the chambers or the tubes, or the rubber or vacuum valves, independently.

What we do claim as our invention, and desire to secure by Letters Patent, is—

1. A steam-condenser having the chambers *A* divided into compartments and provided with tubes *g*, diminishing in number in each compartment, substantially as shown and described, for the purpose set forth.

2. In a steam-condenser, the covers *h*, in combination with the pipes *c*, substantially as and for the purpose described.

WASHINGTON R. PITTS. [L. S.]
GEORGE K. GLUYAS. [L. S.]
